UNITED STATES PATENT OFFICE.

MAURICE ALLAND, OF ATLANTIC CITY, NEW JERSEY.

MAGAZINE PENCIL.

Application filed October 3, 1925. Serial No. 60,220.

The object of the invention is to provide improvements in writing instruments and particularly in that type commonly known as magazine pencils.

5 Another object is to provide an instrument of this character, wherein the reservoir of a fountain pen is adapted to be filled with fluid by means of a plunger, and the mechanical details of the pencil are located 10 within the hollow shaft that actuates said plunger.

A further object is to provide an improved construction for assembling the terminal member of the pencil upon the body of the 15 instrument, whereby the former is free to rotate with respect to the latter, and upon necessity can be removed from said body portion, when assembled there being no external evidence of the manner in which the union 20 is maintained.

Still another object is to provide a construction which permits the insertion of a fresh length of lead within the end portion 25 of a holder, while the latter is in extended position in one direction, and upon rotating the terminal operating member until the holder reaches its other extreme position a slender rod extending centrally through the said shaft serves to loosen any portion of 30 the lead still gripped by said holder, so that the lead may be dropped from the instrument solely by gravity when turned into vertical position.

And a still further object is to provide all 35 of these features and others in combination with a unique cap for the instrument, which is adapted to contain a large number of renewal leads of the same or different colors from the one which at any time may be located operatively within the instrument.

With these and other objects in mind, the invention comprises further objects and advantages fully brought out in the following description, when read in conjunction with 45 the accompanying drawings, in which Fig. 1 is a side view of a writing instrument comprising one embodiment of the invention, with the magazine cap shown partly in section and thereby exposing to view the fountain pen portion of the instrument; Fig. 2 is a fragmentary sectional view of a portion 50 of the instrument, showing the pencil portion of the mechanism in diametrical section; Fig. 3 is a group figure showing the several parts of the said mechanism in elevation and in alignment for operative as-

sembly; and Fig. 4 is a diametrical view of certain of the elements shown in Fig. 3 also in alignment.

Referring to Fig. 1 of the drawings, a 60 writing instrument is shown as comprising a central reservoir portion 1, terminating upwardly in the fountain pen portion 2 of the instrument, described in a co-pending application, and normally covered by a magazine 65 cap 3 also described in a separate co-pending application, and containing reserve leads within a cylindrical compartment 4, besides terminating in an eraser 5. The lower end portion of this instrument comprises a 70 magazine pencil section 6, from which the exposed end of a writing lead 7 is shown protruding.

As described in the co-pending application above referred to with respect to the fountain pen, the fluid for the reservoir is forced thereinto by means of a plunger 8, surrounded by a gasket 9 which slidably engages the inner surface of the walls of the said reservoir 1, while said plunger is provided 80 with an axial threaded bore 10 adapted to receive the correspondingly threaded head 11 of a member shown in Fig. 3. The head of this last-named member terminates in one direction in an enlargement 12 which serves 85 to prevent the head from passing entirely through the bore 10 of the plunger, while the opposite end of this head is provided with an axially extending rod 13.

Referring now to Figs. 2 to 4 inclusive, 90 the lower end of the reservoir 1 is spanned by a closure 14 secured into the end thereof, and terminating downwardly in a reduced threaded portion 15, which receives in normally fixed relation a member 16, which is 95 provided with an axial bore 17 in alignment with the corresponding bore 18 of the closure 14. The lower end portion of the member 16 is also reduced at 19 and provided with a circumferential groove 20, in which is positioned, yet but partially embedded, a 100 radially resilient ring 21.

The terminal member 6 comprises any external configuration that may be desired for the sake of utility and convenience, but internally is provided with a bore 22 adapted to slidably receive the reduced portion 19 of the member 16, and with a groove 23 which normally slidably receives one-half of the cross-section of the ring 21, whereby the member 6 is free to rotate upon the member 16. Downwardly the bore 22 opens into a 110

narrower bore 24 into which is secured in any suitable manner the knurled end portion 25 of a cylindrical member 26, the upper portion of which latter is provided with spiral 5 grooves 27, which create spiral ridges upon the interior of said last-named member. The bore 24 opens downwardly into a restricted bore 28 through which the lead 7 is free to slide and to project when the instrument 10 is employed for writing as a pencil.

Within the member 26 is a further cylindrical member 29, which is provided with spiral grooves 30 preferably throughout its entire length, except for its lower end portion 31, which latter is restricted and is provided with an inwardly tapering bore which normally receives the inner end portion of the lead 7. The grooves 30 cooperate with and engage the ridges caused by the grooves 27 in the member 26, so that when the member 6 is rotated, and the member 26 is thereby likewise rotated, the member 29 is caused to reciprocate through said member 26, since it too cannot rotate, being provided with a lug 32 which is slidable within the longitudinal key-way or slot 33 of a cylindrical member 34, supported fixedly within the member 16 and surrounding the member 26, the upper end of the member 34 being reduced at 30 35 and secured within the recessed portion of the head 11, so that the rod 13 extends therethrough and in reciprocatory relation with the member 29, though longitudinally fixed with respect to the members 26 and 34.

35 In the operation of the device as illustrated and as above described, the various parts are assembled as shown in Fig. 2, and the member 6 is rotated so that the member 29 approaches the lower end of the instrument (when held as shown in Figs. 1 and 2). One end of a lead 7 is then inserted through the bore 28 and into the tapered bore of the lower portion 31 of the member 29, so that the lead is thereby gripped and operatively secured with each

application of the pencil to the writing material. The member 6 is then rotated in the opposite direction until the member 29, carrying the lead with it, rises within the member 26, and the lead is exposed only the desired distance as shown in Fig. 1. Thereafter, as the lead wears away, the member 6 is rotated so as to reciprocate the member 29 and bring a greater portion of the fresh lead into exposed position and available for writing. However, if while using a lead of a given color, it is desired to change to a lead of a different color, the member 6 is rotated so as to cause the member 29 to retreat to its farthest inward position, where the rod 13, 60 extending through the member 29 comes into contact with the remaining piece of lead and loosens the same from its normal position wedged within the member 31. The lead is then free to drop by gravity from the instrument, and thereafter the holder member 29 may again be brought to a forward position and the desired new lead inserted therein.

Having thus described my invention, what I claim and desire to protect by Letters Patent of the United States is:—

A writing instrument comprising a pen having a reservoir, a suction plunger therein, a closure for one end of the reservoir, a hollow shaft extending from one end of the plunger and below said closure and slidably through the latter, an actuating member on said shaft detachably connected to said closure, an actuating member carried by and rotatable relatively to the first mentioned actuating member, a rotatable sleeve substantially within said shaft partly extending below the same and to which the second actuating member is secured, and means within and coacting with said shaft and sleeve to hold and feed lead.

In testimony whereof I have affixed my signature.

MAURICE ALLAND.
